ROAD STRIPING MACHINE WITH ELECTRONIC SIGHT

Carl F. Brown, Jr., Huntingdon, Pa., assignor to Wald Industries, Inc., Huntingdon, Pa., a corporation of Pennsylvania

Filed Sept. 23, 1959, Ser. No. 841,868

7 Claims. (Cl. 239—150)

The present invention relates to a road striping machine, and more particularly to a road striping machine in which a closed television circuit is utilized for guiding the machine.

The application of guide stripes to roadways is now common practice, and over the years equipment has been developed to enable the various stripes necessary to be applied to the roads. Typically, the road striping equipment comprises a vehicle such as a truck, which truck supports suitable tanks for paint and compressed air, as well as an air compressor. The truck also supports a spray gun which is supplied from the paint and compressed air tanks and is directed downwardly so as to apply or deposit a stripe on to the roadway.

The positioning of the spray gun is accomplished by steering the truck, and thus the place on the roadway where the stripe is applied depends upon the steering of the truck, and to aid the driver of the truck to steer it to properly place the stripe on the roadway, it has been the practice to provide a pointer, carried by a boom, that extends forwardly from the front of the truck. Such boom and pointer arrangements constitute the guide device which is most commonly used in practice today.

Other guide devices have been suggested by the workers in the art, but only the above-mentioned boom and pointer apparatus have actually gained wide commercial acceptance.

While the boom and pointer construction offer advantages over the other known guide devices, it is nevertheless true that in order to position the pointer sufficiently far ahead of the driver of the truck that it may adequately serve its purpose, the boom has to be of considerable length. These booms must, therefore, be moved to a carrying position for movement of the truck to and from the job site, and in the carrying position there is some obstruction to the view of the driver. Further, these booms, when in use, rest on a swiveled front support wheel. As this wheel often vibrates during the spraying operations, there results misalignment of the boom and pointer and inaccuracy in the laying of the paint stripe. In addition to the inaccuracies inherent in the boom, the boom, in operative position does constitute somewhat of a traffic hazard, since approaching vehicles do not appreciate that the boom is extending in front of the road striping truck, and since the boom must enter an intersection ahead of the vehicle itself.

It will be understood that the booms are primarily used where an existing guide stripe has become worn and therefore partially obliterated, and it is desired to repaint the stripe in order to make it more visible. There is also presented, in road striping, the problem of laying a stripe initially on the road and in properly positioning this initial stripe. Equipment heretofore suggested for the application of a new stripe has not been entirely satisfactory, as it has required either a relatively slow movement of the paint striping machine, or has required that a guide marking be applied to the roadway to serve the same function as the partially obliterated stripe above referred to.

An object of the present invention is to provide a road striping machine having a highly accurate guide device.

Another object of the present invention is the provision

2

of a road striping machine having a guidance arrangement that offers no impediment or obstruction during either road striping operations or during transit to and from the job site.

Yet another object of the present invention is to provide a road striping machine wherein the guiding arrangement does not constitute, in any way, a traffic or safety hazard.

Still another object of the present invention is the provision of a road striping machine that will enable the painting of an initial highway guide stripe with accuracy and rapidity.

Other objects and the nature and advantages of the instant invention will be apparent from the following description taken in conjunction with the accompanying drawings, wherein:

FIG. 1 is a perspective view of a part of a road striping machine in accordance with the present invention.

FIG. 2 is a plan view of the road striping machine of the present invention.

FIG. 3 is a representation of a television receiver forming part of the road striping machine of FIG. 1.

FIG. 4 is a plan view of another embodiment of a road striping machine in accordance with the present invention and particularly adapted to the application of an initial stripe on a roadway.

FIG. 5 is a representation of an image produced on a television receiver forming part of the invention of FIG. 4, and showing the image produced when the road striping machine is out of proper position.

FIG. 6 is a view similar to FIG. 5 and illustrating the television receiver when the machine is in proper position.

Referring now to the drawings wherein like reference numerals are used to designate like or corresponding parts throughout the several views, there is shown in FIG. 1 a road striping machine 10 comprising a truck 11 having a cab 12 thereon. Truck 11 also has, in known manner, an air compressor, an air tank and a paint tank thereon, not shown. The control box 13 may be provided, and from the control box 13 there extend suitable air and paint lines 14 and 16 to a spray gun 17. Rearwardly of paint spray gun 17 there is positioned a bead dispenser 18, also supplied by conduits 19 and 20 from control box 13.

The spray gun 17 and bead dispenser 18 are suitably supported on a carriage 21, which is supported from the truck 11, by a support tube 22 and a pneumatic or hydraulic cylinder 23.

In the cab 12 of truck 11 there may be seen the usual steering wheel 25, and forwardly of the steering wheel 25 there is a television receiver 26. Television receiver 26 is connected with a television camera 27, which is supported on the truck 11, and may conveniently be supported on tube 22. Television camera 27 is directed at the roadway, in the preferred embodiment slightly ahead of and to the left of the truck 11, although it will be understood that the television camera 27 may be otherwise directed as requirements dictate.

Referring now to FIG. 2, it may be seen that the television camera 27 is focused upon the stripe S which will be understood to be an old, partially obliterated guide stripe. Television camera 27 and television receiver 26 form part of a closed television circuit 28, shown diagrammatically in FIG. 2.

In FIG. 3 there may be seen the television receiver 26 having lines 30 and 31 thereon. The lines 30 and 31 are in spaced parallel relation on the screen of receiver 26, and extend generally vertically on either side of the vertical middle line thereof. There is also shown in FIG. 3 the image produced on screen 26 when the machine 10 is properly oriented in relation to the old stripe

S, there being shown an image 32 of the stripe S, equally spaced between the lines 30 and 31, and parallel thereto.

In the operation of the road striping machine 10, the truck 11 is steered along and adjacent to the stripe S which is to be repainted. The television camera 27 is focused on the stripe S closely adjacent the truck 11, and transmits an image of the stripe S, which is reproduced on the television receiver 26. By using this image of the stripe S, the driver of the truck 11 may so steer the truck that paint sprayed from spray gun 17 will be deposited on to the old stripe S with a high degree of accuracy. The driver of truck 11 will be able to repaint the stripe S, with the noted high accuracy, whether the truck 11 is traveling over a road that is either straight or curved, and whether the road is relatively smooth or rough. Errors in the application of the paint from spray gun 17 are substantially avoided and so the desired result of a repainting of the old line is readily accomplished. Since the television screen 26 is directly forward of the steering wheel 25, the driver will have no problem of lining up a relatively remote pointer with the old stripe S, and may more easily attend to the various functions which are necessary during the spraying operation.

For initially painting the stripe on the roadway, such as on a newly completed roadway or on a roadway in which the old stripe has become too faint to serve as a guide, there is provided the road striping machine 40 shown in FIGS. 4-6. Road striping machine 40 has, in general, the same paint spraying equipment as the road striping machine 10, and comprising a spray gun 17. On road striping machine 40 there are provided a first television camera 41 and a second television camera 42, which are focused on the left and right edges 43 and 44, respectively, of a road R. The television cameras 41 and 42 comprise part of a closed television circuit 45, circuit 45 also comprising a television receiver 46. The television cameras 41 and 42 are shown directed forwardly and diagonally of the road striping machine 40, but it will be understood that this position is exemplary only.

On the receiver 46, in FIG. 5, there may be seen an image 47 of road edge 43, as received by camera 41, and spaced therefrom there may be seen an image 48 of road edge 44 received by camera 42. These images 47 and 48 are shown in FIG. 5 to be spaced from each other, and thus indicate to the driver of the road striping machine 40 that the machine 40 is not in the proper position relative to the edges 43 and 44. By properly steering the machine 40, the images 47 and 48 may be caused to coincide, as shown in FIG. 6.

The road striping machine 40 provides for the application of a new stripe in proper position on a roadway on which there is no guidance for the stripe, either by previously laid guide marks, or by an old, partially obliterated stripe. The stripe laid by the machine 40 will be accurately located on the roadway R, and may be placed with relatively great rapidity, to thereby reduce the cost of the stripe application by increasing the length of stripe that will be applied in a given time.

There have been provided road striping machines utilizing closed television circuits to enable a stripe to be applied to a road with safety and accuracy. The machines, in accordance with the invention, may either use a previously laid stripe as a guide line, or may, alternatively, apply a stripe with accuracy where there is no such guide line.

It will be obvious to those skilled in the art that various changes may be made without departing from the spirit of the invention and therefore the invention is not limited to what is shown in the drawings and described in the specification, but only as indicated in the appended claims.

What is claimed is:

1. A road striping machine for placing a painted band on a roadway comprising a steerable vehicle, means on said vehicle for applying a band of paint on the roadway

supporting the vehicle, a television camera carried by the vehicle and directed towards the roadway adjacent the vehicle to thereby receive an image of the band on the roadway, and a television receiver positioned on said vehicle to be viewed by the driver thereof, said television camera and television receiver being parts of a closed television circuit, said television receiver having a pair of generally vertically extending parallel lines thereon, whereby said vehicle may be steered to accurately repaint a band on the roadway.

2. A road striping machine comprising a steerable vehicle, means on said vehicle for applying a band of paint on the roadway supporting the vehicle, a television camera carried by the vehicle and directed towards the roadway adjacent the vehicle to thereby receive an image of a band on the roadway, and a television receiver positioned on said vehicle to be viewed by the driver thereof, said television camera and television receiver being parts of a closed television circuit, said television receiver having a pair of parallel lines thereon, whereby said vehicle may be steered to accurately repaint a band on the roadway.

3. A road striping machine comprising a steerable vehicle, means on said vehicle for applying a band of paint on the roadway supporting the vehicle, a television camera carried by the vehicle and directed towards the roadway adjacent the vehicle to thereby receive an image of a band on the roadway, and a television receiver positioned on said vehicle to be viewed by the driver thereof, said television camera and television receiver being parts of a closed television circuit, said television receiver having guide means on the screen thereof, whereby said vehicle may be steered to accurately repaint a band on the roadway.

4. A road striping machine comprising a steerable vehicle, means on said vehicle for applying a band of paint on the roadway supporting the vehicle, a pair of television cameras carried by the vehicle and directed at the edges of the roadway which is to have a paint band applied thereto, a television receiver positioned on said vehicle to be viewed by the driver thereof, and closed circuit television means comprising said two television cameras and said television receiver for impressing the images received by said cameras on said receiver, said television cameras tilted at such an angle so as to place the images of the edges of the roadway generally in the center of said television receiver when the means for applying the band of paint is centered in the roadway, whereby said vehicle may be steered in accordance with the images on said television receiver to apply a paint band on the roadway.

5. A road striping machine comprising a steerable vehicle, means on said vehicle for applying a band of paint on the roadway supporting the vehicle, a pair of television cameras carried by the vehicle and directed at the edges of the roadway which is to have a paint band applied thereto, a television receiver on said vehicle, and closed circuit television means comprising said two television cameras and said television receiver for superimposing both images received by said cameras together on said receiver, whereby said vehicle may be steered in accordance with the images on said television receiver to apply a paint stripe on the roadway.

6. A road striping machine comprising a steerable vehicle, paint spraying means on the side of said vehicle for applying a band of paint on the roadway supporting the vehicle, a pair of television cameras carried by the vehicle and directed at the edges of the roadway which is to have a paint band applied thereto, one of said cameras attached to the side of said vehicle mounting the paint spraying means and the other of said cameras attached to the other side of said vehicle, a line along the direction of aim of said camera on the side of said vehicle mounting the paint spraying means forming a larger angle with a line through the longitudinal axis of said vehicle

than the angle between a line through the longitudinal axis of said vehicle and a line along the direction of aim of said camera on the other side of said vehicle, and a television receiver positioned on said vehicle to be viewed by the driver thereof, said television receiver forming a closed television circuit with said cameras, and said television cameras tilted at such an angle so as to place the images of the edges of the roadway generally in center of said television receiver when the paint spraying means is centered in the roadway whereby said vehicle may be steered to accurately apply a paint band on the roadway.

7. The road striping machine of claim 6, further characterized by said television receiver having circuitry to

impress images from both of said cameras on said receiver at the same time.
